UNITED STATES PATENT OFFICE

JAMES N. WHITE, OF DENVER, COLORADO

CYLINDER LAUNDRY MACHINE

Application filed July 29, 1927. Serial No. 209,294.

This invention relates to cylinder laundry machines and particularly to that class thereof in which there is an outer cylindrical tub within which is revolvably mounted a cylindrical clothes container.

An object of the invention is to provide improvements in the structure and operation thereof with relation to the dumping of the clothes from the machine after the clothes have been washed or dried within the machine, it being understood that while the machine is here described as a washing machine it can, with appropriate additions not affecting the features involved in the present invention, be as well used for drying clothes.

A further object is to provide for the dumping of the clothes from the machine by providing for the revolvability of the tub as well as for the revolvability of the container with relation to the tub.

Other objects will appear from the following specification and claims as illustrated in the accompanying drawing in which like characters of reference indicate corresponding parts throughout and in which:

Fig. I is a front elevation of a four-compartment machine showing the left half of the tub closed, with clothes receiving bags as placed upon the bag racks and not in operative position, and showing the right half of the tub open, disclosing the clothes container, which container is shown closed as to one compartment and open as to another and also showing a fragment of the bag rack in place in the said open compartment at the right of the figure.

Fig. II is a section on line A—A of Fig. I.

Fig. III is a section on line A—A of Fig. I but showing the machine at the limit of movement in the dumping operation with bags in operative position for receiving the clothes.

Fig. IV is an end elevation with part of the casing broken away.

Fig. V is a fragmentary view illustrating the use of a motor in place of hand crank for dumping operation.

Fig. VI is a detail of the combined bag rack and dumping frame.

Fig. VII is a fragmentary enlarged detail

view in cross section showing the parts at and adjacent the point of attachment of the bag rack to the tub.

I provide standards 1, which may be bolted to the floor as indicated at 2, and which support suitable bearings 3 on which tub 4 revolvably rests, the tub being provided with bearing bands 5 and, at one end, with a rack 6 engaged by pinion 7 revolvably mounted in casing 8 and provided with crank 9 whereby tub 4 may be revolved. A modified structure for revolution by motor is illustrated at Fig. V.

Tub 4 is provided with doorways 10 shown at the right in Fig. I and which may be closed, while the machine is operating for washing or drying, by doors 11 sliding in runways 12 which may be formed in any suitable manner as by the inner wall of the tub and strips 13 attached thereto at their ends as at 14 but elsewhere spaced therefrom to form the runways. The doors 11 are provided with handles 11^a for opening and closing the same.

Tub 4 is provided with a suitable outlet structure generally indicated at 15 which is arranged for opening and closing through shaft 16 and lever 17 by handle 18 all mounted on the tub so as to revolve therewith.

A clothes container 19, cylindrical in shape and suitably perforated for freely permitting ingress and egress of washing fluid, is revolvably mounted in and with reference to the tub by suitable means as shafts 20 projecting from the central part of the ends of the container into suitable bearings 21 in the ends 4^a of the tub, one of said shafts 20 projecting through its bearing 21 and carrying a cogwheel 22 whereby the container may be revolved, power from any suitable source being transmitted through pulley 23 and thence through any suitable arrangement of gears, not shown but contained within and indicated by casing 24, to cogwheel 22. A suitable casing 25 is provided for enclosing this container-driving mechanism and the casings 8 and 25 are held in position by construction integral with standards 1 or suitable mountings on standards 1 as at 26. In either case brace rod and adjusting nuts 27

and 28 hold the tops of the casings in properly adjusted and spaced relation. Such construction leaves the space beneath the tub clear for dumping purposes.

5 Clothes container 19 may be, and in practice usually will be, divided by transverse partitions 29 (indicated in dotted lines) into compartments each of which has a doorway 30 substantially co-extensive with the width of the compartment and which is opened and closed by a door 31 preferably having material and perforation similar to the container, and sliding in runways formed by curved strips 32 attached as at 33 to the wall of the 10 container and suitably spaced therefrom to form the runways. Suitable catch-handles 34 are provided for operating the doors 31 and for locking the doors 31 in closed position while the machine is washing or drying.

20 Liquid may be supplied to the tub through pipe 35 having a valve 36 and a swinging joint 37 to permit the revolution of the tub while maintaining connection with the pipe.

A combined rack and dumping frame 38 is 25 shown at Fig. VI, having hinges 39 whereby to hinge the rack to the tub at the edge of the doorways 10 and having cut-outs 40 substantially co-terminous with the doorways 30 in clothes container 19. Flanges 41 serve 30 the triple purpose of forming means for holding the receiving bags 42, see Figs. II and III, locking the tub 4 and clothes container 19 in position with their respective doorways 10 and 30 aligned by projecting through said 35 aligned doorways, see Fig. III, and forming guides for the clothes in passing from the container 19 to and through the doorways 30 in container 19 and 10 in tub 4. This rack may be used as a dumping frame, without the 40 use of the bags 42 for receiving clothes, and in such case the flanges 41 while not serving the purpose of bag supports still serve their other two purposes of interlocking the tub and container and forming guides for the 45 clothes.

A brace member 43 hinged to the edge 44 of the bag rack 38 may be provided for supporting the bag rack in position shown in Figs. I, II, and IV while the bags are being 50 placed upon the rack, whereupon, if the machine is not ready for dumping, the brace may be swung upon its hinge into the plane of the body portion of the rack 38 in which 55 position it will be out of bracing engagement with the tub 4 and will permit the rack 38 to drop and hang from its hinge 39, in which position the rack will be out of the way so far as operations in the front of the machine are concerned. The brace member is not 60 essential but is a convenience for use in attaching the bags to the racks.

To operate the machine, the doors 11 of tub 4 are opened and likewise the doors 31 of container 19. The container and the tub are 65 then locked in position with their respective

doorways in alignment. The locking may be accomplished by throwing the rack 38 into position in the doorways as indicated at the right in Fig. I with flanges 41 extending through and adjacent the sides of the aligned doorways 10 and 30 as further illustrated, though in dumping position, at Fig. III. Clothes are then placed in the container 19 through the aligned doorways. The lock is released by throwing back rack 38 thus withdrawing flanges 41 from the doorways, and all openings are closed. The washing fluid is provided either before or after the clothes are inserted and through the pipe 35 or through the doorways 10 and/or 30 as desired. If the fluid is to be provided after the openings are closed, obviously it must be provided through the pipe 35. Thereupon the container 19 is revolved by the mechanism above described until the washing operation is completed. Thereupon the outlet mechanism 15 is operated for draining the tub. The doors 11 are then opened, the tub during this operation having remained in substantially the position shown in Fig. I. The container is then revolved until the doorways 30 are in alignment with the doorways 10 whereupon the doors 31 are opened and racks 38 are swung into position with the flanges 41 extending through the aligned doorways. If the bags 42 are to be used for receiving the clothes, they will, of course, have been attached to the racks prior to the swinging of the racks into operative position as above described. After the racks are placed in the operative position above described the tub, and therewith the interlocked container, is revolved by crank 9 until both tub and container reach the position shown in Fig. III, at which point all of the clothes contained within the container will have fallen through the aligned doorways and into the bags 42, or any other suitable receptacle which may be provided beneath the tub, whereupon by means of the crank 9 the tub and container are returned to the position shown in Fig. I and the operation is repeated.

At Fig. V is illustrated a rack 45 placed on the end of the tub 4 and a pinion 46 meshing therewith and operated by motor 47 for accomplishing the revolution of the tub by power from such motor. Snap switch 48 is provided operable by fingers 49 for automatically breaking the circuit when the end of the rack 45 is approached in the revolution of the tub in either direction. Any suitable mechanism, switch and circuit for this purpose may be provided.

Should the revolution of container 19 tend to cause tub 4 to revolve, the tub may be held against such tendency by any one of many obvious mechanical expedients as, for example, hook 50 around pipe 35 and crank 9.

Many parts and constructions herein de-

scribed may be changed to those which are standard and/or commonly employed in this art or to any mechanical equivalent, and other changes in structure may be made, without affecting the spirit or substance of this invention and within the scope of the claims.

I claim:

1. In a laundry machine, a rotatable tub, 10 a cylindrical container rotatable within the tub, means for rotating the container while holding the tub stationary, doorways in the container and in the tub adapted to be relatively aligned and a frame insertable in said doorways and having means for maintaining said alignment and for forming a passage from the interior of the container to the exterior of the tub.
2. In a laundry machine, a rotatable tub, 20 a rotatable cylindrical container within the tub, means for revolving the container independently of the tub, means for revolving the container and the tub in relatively interlocked relation, relatively alignable doorways in the container and tub and a frame insertable in the doorways when aligned for maintaining the alignment, said frame having means for carrying a laundry bag with its open end distended to substantially surround the opening formed by the aligned doorways.
3. In a laundry machine, a rotatable cylindrical tub, a rotatable cylindrical container within the tub, an intervening space 35 between the cylindrical tub and the cylindrical container, means for revolving the tub and the cylinder independently of each other, means for revolving the tub and container in relatively interlocked position, alignable doorways in the container and tub and a frame insertable in the doorways when aligned for maintaining the alignment and having means for closing said intervening space adjacent said doorways.
4. In a laundry machine, a rotatable tub, a 45 rotatable container within the tub, means for revolving the tub and cylinder independently and also coincidentally, relatively alignable doorways in the tub and container and a combined bag-rack and dumping frame insertable in said doorways when aligned and having flanges projecting through the aligned doorways for maintaining said relative alignment and for guiding the clothes in passage through said aligned doorways, said flanges being also adapted to carry a bag in distended position substantially covering the opening formed by the aligned doorways.
- 50 In testimony whereof, I affix signature.
JAMES N. WHITE.
